PORTABLE ELECTRIC FLASHLIGHT

Bernard Francis Muldoon, Caldwell, N. J.,
assignor to Henry Hyman, New York, N. Y.

Application September 21, 1943, Serial No. 503,183

5 Claims. (Cl. 240—10.67)

This invention relates to portable electric flashlights.

The main object of the invention is to provide in a flashlight having a casing of insulating material and a reflector which carries current to the lamp, a highly improved means for effecting one leg of an electric circuit between said lamp and a battery in the casing.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

Certain features shown and/or described and not claimed herein are shown, described and claimed in my copending applications Serial No. 377,983, filed February 8, 1941, and Serial No. 503,182, filed September 21, 1943.

In the accompanying drawing, in which is shown one of the various possible embodiments of this invention,

Fig. 1 is a front to back central longitudinal section through a flashlight embodying the invention;

Fig. 2 is a longitudinal section taken substantially along the line 2—2 of Fig. 1;

Fig. 3 is a sectional view through the head of the flashlight taken substantially along the line 3—3 of Fig. 2; and

Fig. 4 is a view similar to Fig. 3 with the head assembly removed.

Referring now in detail to the drawing, the flashlight 10 embodying the invention there shown comprises a battery casing 12, a head assembly 14, a base assembly 16 and an electrical system which includes a switch 18 and various parts of the head and rear assemblies.

By way of example, the casing 12 is for the angle head type of flashlight and consists of a body portion 20 of cylindrical tubular shape and an integral angularly disposed cylindrical tubular head portion 22 molded from plastic electrically non-conductive material such as phenol condensate or cellulose acetate butyrate.

Between the head and body portions is provided a partition 24 which comprises a continuation of a wall of the head casing portion 22 inside of the casing 12, said wall thus being of arcuate substantially semi-circular configuration as shown in Fig. 2.

The body casing portion 20 houses a source of energy such as a set of batteries B, the lowermost of which compresses a battery spring 26 which bears against the zinc cup thereof. Said battery spring rests against a ledge 28 in a bottom closure cap 30 and contacts a ferrule 32 nested in the bottom of the body portion of the cas-

ing. The ferrule in turn is in electrical contact with an electrically conductive strip 34 running to the switch 18.

The switch 18 is adapted to make and break an electric circuit between the conductive strip 34 and another electrically conductive strip 36. Said second strip lies in a channel 38 formed by a pair of spaced ridges 40, 42 extending parallel to the longitudinal axis of the body portion 20. The channel 38 extends through an opening 39 in the partition 24 to permit the strip 36 to pass freely from the interior of the body portion to the interior of the head portion.

At the upper end of the strip there is provided an angled extension 44 which runs from the strip toward the front of the head in a direction substantially parallel to the longitudinal axis of the head portion 22. The tip of this angled extension 44 is adapted to make electric contact with the electrically conductive parabolic reflector 46 which itself is in electric contact with one of the terminals of the lamp 48.

However, it has proven extremely difficult to insure good contact between the tip of this angled extension and the reflector, particularly where the casing is of a molded plastic material. To overcome this difficulty and provide an inexpensive, simple and positive electrical connection between the battery and a reflector, the following construction is employed:

A small tapered pin 50 integrally extends from the casing. Said pin runs parallel to the longitudinal axis of the head casing portion 22 and is secured thereto by an integral wall 52 which stops short of the tip of the pin so as to provide a slot 54 whose walls are spaced radially of the longitudinal axis of the head portion of the casing and which faces toward the front of said portion.

The interior diameter of the front end of said head portion is enlarged and provided on its outer surface with threads which are adapted to mesh with the female threads of a lens ring 56. Said lens ring clamps a lens 58 and a flange 60 on the parabolic reflector 46 between the lens ring and the forward end of the head portion 22. Due to the enlargement of the forward end of said head portion a flaring fillet 62 is formed between the part of the casing including the slot 54 and the part of the casing which receives the lens ring. The high point of this fillet is so situated as to interpose an obstruction between the inner wall 54a of the slot 54 and a point 55 in the inner front edge of the head casing portion 22 lying in the same radial plane as said slot.

Due to the presence of this obstruction, when the head assembly, including the reflector 46, is mounted on the head casing portion 22, the reflector will first contact the tip of the angled

extension 44 while it is disposed in its relaxed position shown in Fig. 4. As the reflector is urged inwardly it will force the tip of said extension outwardly. This first results in shifting the conductor 36 away from the inner wall 54a of the slot, into engagement with which it is biased when relaxed, and urging said conductor against the outer wall 54b of the slot. Further radially outward shifting of the tip of the angled extension portion 44 will bow said extension 10 across the fillet 62 stressing the same and causing it to be strongly pressed against the slot wall 54a and reflector 46, as shown in Fig. 3. This construction thus insures good electrical contact between the extension and the reflector and firmly anchors the upper end of the extension in position once the head assembly has been screwed on the casing.

It will be appreciated that since the foregoing construction firmly secures one end of the strip 36 in position, the latter need be held to the casing at but one more point and must be so mounted that said tip will be engaged automatically by the reflector 46 during positioning of the head assembly. Accordingly said strip is permanently secured to the casing only by a rivet 64 which electrically connects the strip to the switch 18. Although the rivet binds the strip against the casing the strip may be rotated about said rivet and it is maintained in proper position for contact with the reflector by its disposal in the channel 38. In addition, since the strip passes through the opening 39 in the partition 24, it cannot be angularly deflected, even accidentally, to such a position that it will not engage the reflector during mounting of the head assembly.

It will be noted that when the tip of the strip 36 engages the reflector the strip may be rotated about the rivet 64 and forced against the base of the slot 54. This further serves to securely anchor the strip in the casing so that a good electrical contact will be maintained between the strip and the reflector as long as the head assembly is in position.

It will be understood that the foregoing construction can be employed in any flashlight wherein one leg of the electric circuit which energizes the lamp 48 from the batteries B includes the reflector 46 for such lamp. By way of example, I have illustrated one such flashlight in which an electrically conductive threaded ferrule 66 is clinched around the opening at the rear of the reflector in such manner as to provide an inwardly directed flange 68 against which the flange 70 of the lamp 48 is seated. The lamp flange is held in this position by a plug 72 of insulating material which is screwed into the ferrule. Said plug has a central bore through which the lamp base freely passes. The central terminal 74 of the lamp extends beyond said plug to engage a resilient electrically conductive contact 76 which is fixed to the partition 24 by a rivet 78. This rivet extends through the partition to contact the central electrode 80 of the uppermost battery thus completing the energizing circuit for the lamp when the switch 18 is closed.

It will thus be seen that I have provided a device in which the several objects of the invention are achieved, and which is well adapted to meet the conditions of practical use.

As various possible embodiments might be made of the above invention, and as various changes might be made in the embodiment above

set forth, it is to be understood that all matter herein set forth or shown in the accompanying drawing is to be interpreted as illustrative and not in a limiting sense.

Having thus described my invention, I claim as new and desire to secure by Letters Patent:

1. A portable electric flashlight comprising a casing of insulating material, a head assembly adapted to be detachably mounted on one end of said casing, the head assembly receiving portion of said casing being hollow and having an internal protuberance, said assembly including a reflector of electrically conductive material which is moved longitudinally inwardly of said portion during mounting of the head assembly and a lamp whereof one terminal is in electrical contact with said reflector, said reflector being included in one leg of an electric circuit for energizing said lamp from a battery in the casing, an electrically conductive strip inside and extending longitudinally of said casing portion, the tip of said strip being so disposed as to engage said reflector during mounting of the head assembly and be forced radially outward thereby, another part of said strip being so disposed as to be forced against and pivoted upon said protuberance as said tip is moved radially outwardly, and still another part of said strip being so disposed as to be forced radially inwardly as said strip pivots about said protuberance, and means to restrict the radial inward movement of said last named strip part whereby the strip will be bowed as its tip is forced radially outwardly during mounting of the head assembly so that the strip is anchored and good electrical contact is secured between said strip and the reflector.

2. A flashlight as set forth in claim 1 wherein the means for restricting radial inward movement of the strip part comprises a pin integrally formed with said casing and having a portion thereof spaced radially inwardly therefrom to provide a slot between the pin and the casing.

3. A flashlight as set forth in claim 1 wherein the forward end of the casing portion whereon the head assembly is mounted has an inner diameter greater than the inner diameter of the portion of the casing on which means is provided to restrict inward radial movement of the strip part, and wherein the protuberance about which the strip pivots comprises the section of the casing at which the inner casing diameter is enlarged.

4. A flashlight as set forth in claim 1 wherein the casing has a body portion integrally connected to the head assembly receiving portion and disposed at right angles thereto, said two casing portions having an integral partition therebetween which is disposed within the casing and wherein the conductive strip has an angled leg freely extending through said partition and anchored in said body portion.

5. A flashlight as set forth in claim 1 wherein the casing has a body portion integrally connected to the head assembly receiving portion and disposed at right angles thereto, said two casing portions having an integral partition therebetween which is disposed within the casing and wherein the conductive strip has an angled leg freely extending through said partition and anchored in said body portion at a single point about which it may be rotated.

BERNARD FRANCIS MULDOON.
